UNITED STATES PATENT OFFICE.

HENRY W. SPANG, OF READING, PENNSYLVANIA.

IMPROVEMENT IN ELECTRIC RAILWAY SIGNALS.

Specification forming part of Letters Patent No. 140,737, dated July 8, 1873; application filed April 12, 1872.

To all whom it may concern:

Be it known that I, HENRY W. SPANG, of Reading, in the county of Berks and State of Pennsylvania, have invented a certain Electrical Railway-Signal Apparatus, of which the following is a specification:

The invention relates to displaying safety or danger signals when a railway track between given points is either clear or obstructed, or when a train is approaching a street or road crossing, and to such other purposes as it may be applicable.

Figure 1 is a front elevation. Fig. 2 is a side view. Fig. 3 is a plan view. Figs. 4 are detail views.

A is an electro-magnetic apparatus, which is placed at any suitable point of a railway for indicating the condition of the track between the points B C, Fig. 3, taken at will, and at such height as to be easily discernible by the engineer and others connected with the train. D D' E E' are pairs of electro-magnets, which are connected by the insulated wires a a'. F F' are also electro-magnets, situated above the electro-magnets D D' E E', and carried by the same housings. G is an armature-lever, which vibrates with the rod b, turning in the housings. H H' are armatures of the same, placed opposite to the magnets of the electro-magnets D D' E E'. The upper end of the lever G is slotted longitudinally to admit the adjustable crank-pin c, which takes into the longitudinal slot d of the crank I of the transverse shaft J. K is a toothed sector on the shaft J; it meshes with the pinion L on the transverse shaft M, which carries the revolving signal-frame N. The signal-frame N on the horizontal shaft M is, in this instance, divided into two parts, designated as red and white, though other divisions and colors can be used. By suitable catches or stops the signal can be arrested at any convenient point of its revolution, whereby the proper safety or danger signal can be shown. O is an armature of the electro-magnets F F'. It is carried by the lever P of the shaft Q. R is a pawl of the same shaft, which meshes with the toothed sector K. S S' are the tracks of a railway. T T' are insulated metallic plates at the side of either rail; but not in contact with the same. U is a battery; e e', its poles. V is an iron bar, which is buried in the earth,

and is connected with the pole e by the insulated wire x. The pole e' connects with the electro-magnet E by the wire x'; the electro-magnet F with the insulated plate T by the wire x²; the magnets E' and F by the wire x³; the magnets D' F' by the wire x⁴; the magnet F' and the contact or insulated plate T by the wire x⁵; pole e' to the electro-magnet D by the wire x⁶. Each electro-magnet of a pair is connected with its fellow also by an insulated wire. The rail S is in contact with the earth, and the electric current is broken. To complete it contact must be made between the insulated plate T and the rail; then an electric earth-circuit will be had with the iron bar V in the ground.

When a car, engine, or other vehicle passes over the insulated plate T the thread of the wheels is the medium of contact between the said plate T and the rail, whereby the electric circuit is completed. The armature H of the electro-magnets E E', and the armature O of the electro-magnets F F', are attracted by their respective magnets at the same instant of time. The armature O unmashes the pawl R and the sector K, thereby leaving the signal-shaft M free to turn. The armature H, being attracted by its magnets, vibrates the armature-lever G, which, through the medium of the crank-pin c, crank I, toothed sector K, and the pinion L, revolves the shaft M of the signal N, causing it to show the red or danger signal. After the car or train has passed over the insulated plate T the electric current is broken, and the armatures refuse to act. The spring f brings the pawl R into the meshes or teeth of the tooth sector, and thereby prevents the signal-frame N from turning, the danger or red signal being displayed to any train following. When the wheels of the train pass over the insulated plate T' the thread of the wheels again complete the electric circuit by connecting the said insulated plate and the rail, by means of the earth circuit, with the iron bar V. The electro-magnets D D' and F F' attract their respective armatures H' and O. The pawl R unmashes from the tooth sector K. The armature-lever is vibrated in a contrary direction to that when the car-wheels completed the circuit at the insulated plate T, and exhibited the red light. This move-

ment revolves the signal-shaft M, and causes the signal-frame to exhibit the white or safety signal, notifying any train following that the track between the points B C is clear. The slotted end of the armature-lever G and the slotted crank I, together with the adjustable crank-pin e, regulate the speed and the degree of motion of the tooth-sector, and, of consequence, the revolving signal N, with respect to the degree of the vibration of the armature-lever.

The signal apparatus can be used for indicating the position of a railway switch by dispensing with the electro-magnets F F', armature O, lever P, shaft Q, and the pawl R, and causing an electric circuit to pass through the electro-magnets D D', and display the safety or white signal when the switch is in its proper position, and transferring, by means of a circuit-changer, the electric circuit to and through the electro-magnets E E', and thereby display the red or danger signal when the switch has been misplaced.

I claim as my invention—

1. An electric railway signal which revolves on or around its center, and the face of which is divided into two or more signals, as shown.

2. The slotted armature-lever G, in combination with the slotted crank I and the adjustable crank-pin e, substantially as and for the purpose shown and described.

3. The toothed sector K, pinion L, shaft J, and the revolving signal N, substantially as and for the purpose shown and described.

4. The toothed sector K, pawl R, shaft Q, lever P, and the armature O, substantially as and for the purpose shown and described.

In testimony whereof I hereunto sign my name in presence of two subscribing witnesses.

HENRY W. SPANG.
